UNITED STATES PATENT OFFICE.

HIRAM D. GUY, OF BEREAL, OHIO, ASSIGNOR TO THE DUNHAM COMPANY, OF BEREAL, OHIO, A CORPORATION OF OHIO.

SOIL-PULVERIZING IMPLEMENT.

Application filed May 31, 1921, Serial No. 473,654. Renewed June 25, 1924.

My invention relates to improvements in soil pulverizing implements and more particularly to that class or type of soil or earth working implements commonly known as 5 "packers and mulchers" in which front and rear gangs of spiral extending packer discs are employed, the ends of the axles of the front and rear gangs being mounted in and connected by oscillatory gang bearing or 10 yoke members, pivotally or flexibly connected to the main implement or draft frame and commonly known as "double gang pulverizers". In this type of implement it is desirable that means be provided 15 whereby certain pre-determined pulverizer or packer discs may be removed from the transversely extending axle shaft and the remaining packer or implement discs be secured in relatively fixed spaced relation to 20 provide suitable spaces to receive the rows of growing crops whereby the soil between such rows may be cultivated or packed and mulched. Heretofore this has been accomplished through what is known as "quick 25 detachable discs" much as disclosed and claimed in Dunham Patent No. 1,237,182, of August 14, 1917.

The primary object of this invention is to provide a generally improved implement of 30 the class mentioned of exceedingly efficient and simple construction, and to eliminate the need of such split or quick detachable discs through the medium of improved oscillatory gang bearing or yoke members attached to 35 and mounted upon the implement or draft frame and to the ends of the gang axle shafts whereby the same may be readily attached to or detached from such draft frame and axle shafts without disassembling or 40 disconnecting the main or draft frame from the oscillatory gang bearing yoke members, so that ordinary one-piece pulverizer discs 45 may be employed and such discs may be readily placed upon or detached from such axle bearing shafts, as well as placed in any desired manner by simply detaching the 50 gang bearing members from the ends of the draft or implement frame, as will herein-after more fully appear.

55 A further and very important object is the provision of improved means of mounting and detachably connecting the oscillatory gang bearing yoke members to the ends of the main implement or draft frame through the medium of improved two-part

or split bearing heads, the gang bearing yoke members being provided with inwardly extending bearing members or lugs extending into said split bearing heads of the draft frame.

60 A still further and very important object is the provision of improved split or two-part bearing heads adapted to detachably receive and contain the ends of the gang axle shafts and axle shaft bearing boxes, whereby said shafts may be readily removed without detaching the oscillatory gang bearing yoke members from the ends of the draft or main implement frame.

65 With the above mentioned and other ends 70 in view, the invention consists in the novel construction, arrangement, and combination of parts, hereinafter described, illustrated in some of its embodiments in the accompanying drawings, and particularly pointed out 75 in the appended claims.

Referring to the drawings, forming a part 80 of this specification, Figure 1, is a top plan view of a soil pulverizer or tillage implement of the double gang trailer type constructed in accordance with this invention;

Fig. 2, a side elevation of the same, the seat supporting spring and seat being detached from the rear gang cross-bar;

Fig. 3, an enlarged cross-sectional view 85 taken through line 3—3 of Fig. 2 and illustrating in particular the detachable bearing portion of the gang bearing yoke member in the split or two-part bearing head of the draft frame;

Fig. 4, a cross-sectional view taken on line 4—4 of Fig. 3;

Fig. 5, a side elevation of the inner side 95 of one of the depending bearing members or brackets of the draft frame, one part of the split or two-part bearing head being removed;

Fig. 6, an edge view of the same;

Fig. 7, a side view of the detachable member of the two-part bearing head, detached; 100

Fig. 8, an edge view of the same;

Fig. 9, a plan view of the underside of one of the oscillatory trailer gang yoke members, detached;

Fig. 10, a view of the inner side of the 105 same;

Fig. 11, a fragmentary view of the inner side of the two-part bearing head of the draft frame with the bearing portion of the trailer gang bearing yoke mounted therein; 110

Fig. 12, a perspective view of one of the rear gang bar supporting members, detached;

Fig. 13, a side elevation of a double gang pulverizer of the balanced type, having its gang bearing yoke members equipped with split or two-part bearing heads for quickly detaching the ends of the axle bearing shafts;

Fig. 14, a similar view showing a slightly modified form of split or two-part axle bearing head;

Fig. 15, a cross-sectional view of same taken on line 15—15 of Fig. 14.

Similar numerals of reference designate like parts throughout all the figures of the drawings.

The improved soil pulverizer or tillage implement comprises a main implement or draft frame consisting, in the present instance of transverse bars 1, provided at their ends with depending bearing members 2, the latter being, in the present instance, in the specific form of bearing brackets terminating at their lower ends in bearing heads 2^a, provided with bearing openings 2^b. The implement or draft frame is adapted to be drawn by means of a centrally located draft bar or tongue 3.

The improved implement preferably comprises front and rear gangs of soil pulverizer discs 4, and 5, respectively, the front pulverizer or packer discs 4, being preferably larger in diameter than the rear disc 5, and as a means of removably and adjustably mounting said discs 4, and 5, and providing means whereby an oscillatory or rocking movement will be permitted to said front and rear gangs of discs to conform to or meet the varying contour of the surface being cultivated, front and rear axle shafts 6, and 7, respectively, are provided, the discs 4, and 5, being provided with suitable openings forming bearings and being loosely mounted on the shafts 6, and 7.

As a means of so pivotally or flexibly connecting the axles of the front and rear disc gangs to the bearing heads 2^a, of the depending bearing members or brackets of the main or draft frame that the greatest weight and pulling stresses will be transmitted to the front disc gang in view of their taking the initial and more difficult part of the pulverizing operation, oscillatory gang bearing bars or yoke members are arranged between and connected to the ends of the shafts 6, and 7. The oscillatory yoke members or bars may be either in the specific form of trailer gang yokes 8, as shown in Figs. 1, 2, 3, 4, 5, 10, and 11 of the drawings, or in the form of counterbalanced yokes 8^a, as shown in Figs. 13 and 14 of the drawings in which the pivoted connections or points of oscillation between the members 8^a, and the heads 2^a, of the brackets 2, are

between vertical planes passing through the axes of the shafts supporting the respective front and rear gangs but preferably closer to the front shaft 6, than the rear shaft 7, as shown.

As a means of enabling the discs in the respective front and rear gangs to be removed from or adjusted on the rear axle shaft 7, and front axle shaft 6, without dismantling or disassembling the main or draft frame so that if desired certain of the discs or packer wheels may be removed from or rearranged on the shafts 6, and 7, to form spaces or passes for receiving rows of growing crops, the gang bearing or yoke members 8, and 8^a, are arranged to be inserted on or removed from the outer ends of the shafts 6, and 7, and the bearing heads 2^a, of the brackets 2, by providing the ends and intermediate portions of the gang bearing members 8, and 8^a, respectively, with bearing portions or heads adapted to be inserted in the openings 2^b, of the heads 2^a.

In the form of implement shown in Figs. 1, to 12, inclusive of the drawings, the trailer yokes 8, are provided at their rear ends with bearing heads 8^b, having bearing openings 8^c, to removably receive and contain the ends of the rear axle shaft 7, and the front ends of the yokes 8, are provided with inwardly extending pivot bearing portions 8^d, extending into the bearing heads 2^a, of the draft frame, said bearing portions 8^d, in the present instance, being in the specific form of axle shaft bearing boxes adapted to also receive and contain the ends of the front axle shaft 6.

As a means of quickly attaching the combined axle shaft and pivot bearing portions 8^d, of the trailer yokes 8, to the bearing heads of the draft frame without disassembling the latter, the bearing heads comprise what may be termed split or two-part bearing members comprising the relatively fixed bearing heads 2^a, and the detachable or removable bearing member 2^e (see Figs. 7 and 8), the parts 2^a, and 2^e, comprised in the two-part bearings being provided on their inner sides with a circumferential groove 2^d, to removably receive and contain an annular circumferentially extending bearing flange 8^e, on the axle shaft bearing boxes 8^d.

The removable bearing member 2^e, may be readily attached to or detached from the relatively fixed member 2^a, by means of the attaching elements or bolts 2^f, and it will be obvious that when it is desired to detach or rearrange the discs 4, and 5, on the shafts 6, and 7, the axle bearing portions or boxes 8^d, may be readily removed by simply removing one of the fastening elements or bolts 2^f, at one side or the other thereby dropping down the movable member 2^e, sufficiently to enable the heads 8^b, and yokes 8, to be moved laterally from the ends of the axles 6, and 7. If

desired, the outer portions of the bearing heads 8^b and 8^a , may be provided with quick detachable dust excluding caps 8^t . In this form of soil pulverizer implement the rear ends of the trailer yokes 8 , may be connected and held a certain distance apart by means of pivotally connected upwardly extending supports 9 , connected at their upper ends and adapted to support a rear gang cross-bar 10 , the latter being provided with a seat supporting spring 11 , carrying a seat 12 . The rear end movement of the cross-bar 10 , and seat supporting spring 11 , may be limited in any suitable and convenient manner, as for example,—a flexible connection 13 , such as a chain or the like extending between the upper end of the seat supporting spring 11 , and the transverse draft frame 1 . The lower ends of the support 9 , are pivotally connected to upwardly extending lugs 8^s , at the rear ends of the trailer yokes 8 , by means of pivot elements or bearings 9^a , and it will be obvious in view of the relative location of the connections 9^a , and 13 , with respect to the connections 8^t , with the bearing heads of the main frame that the oscillations of the rear gang of discs 5 , will be minimized at the seat 12 .

The counterbalanced yokes 8^a , shown in Figs. 13, 14, and 15 of the drawings, may be secured to the bearing heads 2^a , of the draft frame in any suitable and convenient manner, as for example,—by means of inwardly extending bearing members or lugs 8^b , extending inwardly into the openings 2^b , and, if desired, the bearing members 8^b , may be secured in the bearing heads 2^a , by means of retaining bolts 14 , passing through central openings in the lugs or heads 8^b , with bearing washers 14^a , to engage with inner sides of the bearing heads 2^a , the outer ends of the bolts being provided with nuts 14^b .

As a means of enabling the yokes 8^a , to be quickly attached to or detached from the ends of the axle shafts 6 , and 7 , for removing or rearranging or adjusting any of the discs of the front and rear disc gangs without detaching the pivoted portions of the yokes from the bearing heads of the draft frame, the ends of the yokes 8^a , can be made in split or two-part bearing heads consisting, in the present instance, of a relatively fixed bearing portion 8^i , and a relatively movable bearing member 8^j .

In the present instance, the movable members 8^j , are pivotally or hingedly connected to one side of the block 8^i , by means of pivot bolts 8^k , and the free ends of the movable members 8^j , may be secured in their fixed or assembled positions by means of securing bolts 8^l .

The members of the split or two-part bearings are preferably provided on their inner sides with circumferentially extending bearing grooves 8^m , adapted to receive a corre-

spondingly formed bearing flange 15^a , of a bearing box 15 , removably mounted in the openings when jointly formed by the members of the split bearings, said boxes being preferably closed at their outer ends by means of flanged heads 15^b , adapted to exclude dust from the boxes.

Having thus described some of the embodiments of my invention, what I claim and desire to secure by Letters Patent, is,—

1. In a soil pulverizer, a draft frame provided with depending end bearings, oscillatory gang axle bearing yokes having cylindrical bearing portions in said end bearings, and split bearings on the ends of said yokes.

2. In a soil pulverizer, a draft frame including depending end bearing brackets, disc gangs and axle shafts, gang bearing yokes, provided with inwardly extending bearing portions extending into said depending end bearing brackets, means for permitting insertion and removal of said bearing portions of said yokes from the outer sides of said end bearing brackets and split bearing heads for permitting detachment of said gang bearing yokes from the ends of said axle shafts without detaching said yokes from the bearing brackets.

3. In a soil pulverizer, a draft frame including end bearings, disc gangs and axle shafts, gang bearing yoke members provided with inwardly extending bearing members extending into said end bearings, means for inserting and removing said bearing members of said yokes from the outer sides of said end bearings, and means for securing said gang bearing yoke members to or detaching the same from the ends of said axle shafts without detaching said yoke members from said end bearing members.

4. In an implement of the roller pulverizer type, a transverse draft frame including depending ends terminating in split bearing heads, oscillatory yoke members provided with axle bearing boxes in said split bearing heads, a disc gang carried by said yoke members, and means for securing said yoke members on the outer sides of said bearing heads whereby the same may be detached outwardly from the ends of said disc gang to permit the removal or re-arrangement of the discs.

5. In an implement of the roller pulverizer type, a transverse draft frame including depending end bearing brackets terminating in two-part bearing heads, front and rear disc gangs, oscillatory gang bearing yoke members provided with bearing portions mounted in said two-part bearing heads on the outer sides of the latter, and means for securing said yoke members from the outer sides of said bearing heads whereby said yoke members may be detached outwardly from said bearing heads of said draft frame and the ends of the disc gangs.

to permit the removal or rearrangement of the discs without dismantling said draft frame.

6. In a soil pulverizer implement including a draft frame and depending bearing brackets terminating in detachable bearing heads, front and rear axle bearing shafts, soil pulverizer discs loosely arranged on said shafts, gang bearing yoke members 10 detachably connected within the ends of said detachable bearing heads and arranged at the outer sides of the latter, said yoke members terminating at the ends in bearing heads extending over the ends of said axle bearing shafts, and means for detachably connecting said yoke members at the outer sides of said detachable bearing members and the ends of said axle bearing shafts whereby said yoke members may be detached laterally and said pulverizer discs be removed from or rearranged on said axle shafts without dismantling said draft frame.

7. In a soil pulverizer implement, including a draft frame and depending end bearing brackets terminating in bearing heads, front and rear axle bearing shafts, soil pulverizer discs loosely arranged on said shafts, gang bearing yoke members having inwardly extending bearing members detachably connected within the ends of said bearing heads, said yoke members being arranged at the outer sides of said bearing heads and terminating in split bearing heads, and 35 means including detachable bearing boxes in said split bearing heads for detachably connecting said yoke members to the ends of said axle bearing shafts whereby said yoke members may be detached laterally and said pulverizer discs be removed from or be rearranged on said axle shafts without dismantling said draft frame.

8. In an implement of the class described, a transverse draft frame including two-part end bearing heads, oscillatory gang bearing yoke members mounted in and movable relatively of said two-part bearing heads, and means for securing said yoke members in and detaching the same from

said bearing heads and from the outer sides 50 thereof to permit the removal or re-arrangement of the discs without dismantling said draft frame.

9. In a soil pulverizing implement, a draft frame including end bearings, front 55 and rear disc gangs, gang bearing yokes mounted in and movable relatively of said end bearings, means for inserting and removing said gang bearing yokes from the outer sides of said end bearings, and means 60 for detaching the ends of said gang bearing yokes from said disc gangs without detaching said yoke members from said end bearings.

10. In an implement of the character 65 described, a draft frame including two-part end bearings, two transversely positioned gangs of discs, oscillatory gang bearing yokes located respectively at opposite ends of said gangs and mounted in and movable 70 relatively of said two-part bearings of said draft frame, and means for detaching said yokes from the outer sides of said two-part end bearings and from said disc gangs 75 whereby said yoke members may be moved axially outwardly from said bearing heads and the ends of said disc gangs to permit the removal or re-arrangement of the discs without dismantling said draft frame.

11. In an implement of the class de- 80 scribed, a draft frame including two-part end bearings, two transversely positioned disc gangs and axle shafts, gang bearing yokes having intermediate bearing portions supported in said two-part bearings and de- 85 tachably connecting the ends of said axle shafts to permit the latter and said gangs to move simultaneously vertically and oppositely, and means for movably connecting said gang bearing yokes to the bearings of 90 said draft frame and arranged to permit the gang yokes to be separated from said bearings and said axles without dismantling said draft frame.

In testimony whereof I have affixed my 95 signature.

HIRAM D. GUY.
